G. G. ROBERTS

GLASS BAIT

Filed May 11, 1923

UNITED STATES PATENT OFFICE.

GEORGE G. ROBERTS, OF WASHINGTON, DISTRICT OF COLUMBIA, ASSIGNOR TO THE VIRGINIA PLATE GLASS CORPORATION, OF WASHINGTON, DISTRICT OF COLUMBIA, A CORPORATION OF VIRGINIA.

GLASS BAIT.

Application filed May 11, 1923. Serial No. 638,294.

To all whom it may concern:

Be it known that I, GEORGE G. ROBERTS, a citizen of the United States of America, and a resident of Washington, District of Columbia, have invented certain new and useful Improvements in Glass Baits, of which the following is a full and clear specification.

In the drawing—

10 Fig. 1 is a front elevation, partly broken away; and

Fig. 2 is a vertical sectional view of an apparatus embodying my invention;

15 Fig. 3 is a detail transverse sectional view showing particularly the hinged clamp for locking the parts of the bait-bar together.

Referring to the drawing annexed by reference-characters, 5 designates two semi-cylindrical bars forming together the bait-bar. These two bars are hinged together along their upper edges by means of pintles 6, so that the two halves of the bar gravitate to closed position. Each bar is grooved longitudinally interiorly to form a bead-forming space 7, and the lower meeting-edges of the two halves of the bar are cut away to form a longitudinal slot 8 at the under side of the bait-bar. The ends of the slot 8 and bead-cavity 7 are closed by end-walls 9, which end-walls come together in contact when the hollow bait-bar is closed. The two sections 5 of the bait-bar are each hollowed to form a water-circulating chamber 10.

35 The bait-bar is hung by means of its hinged lugs and pendent hooks 11 to a frame-bar 12, which bar 12 is attached to the lower end of a lifting-bar 13. As usual in plate-glass drawing, suitable mechanism (not shown) is provided for slowly lifting the bait-bar after it has been lowered into contact with the molten mass of glass. Connected to one of the halves of the bait-bar is a series of pipes 14 which connect, through cross-pipe 15, to a common pipe 16. The pipes 14 have communication with the bead-cavity 7 so that, when suction is applied to the common pipe 16, air will be exhausted from said bead-cavity and its connected slot 8.

50 In operation, the bait-bar is lowered in the usual manner until the lower edge of the bar is immersed in the molten glass, thus sealing the slot 8; then air is exhausted from

the interior of the bait-bar by means of the 55 piping, whereupon the molten glass is drawn up to fill the slot 8 and the cavity 7; then the bait is ready to be raised slowly in the usual manner. By this manner of securing a connection between the plate and 60 the bait, it will be observed that I insure a uniform, complete connection throughout the width of the plate and that, therefore, there is no danger of the plate pulling away from the bait during the lifting process. 65 After the plate is drawn and the glass is cooled, the plate may be readily separated from the bait by simply swinging open the two halves of the bait-bar on the hinges 6. The halves of the bait-bar come away from 70 the glass clean in view of the fact that the glass not only contracts to a greater degree than the metal of the bait, but also contracts quicker; the bait is therefore in condition to be immediately used again for another drawing operation. It will be observed, therefore, that my form of bait-bar does away with the known objections to the usual solid bait-bar.

To insure the sections of the bait-bar 80 being held closely together during the suction operation as well as the drawing operation, I provide one or more clamps 17, each of which consists of an arched member pivoted at 18, at one side of the bait, and 85 adapted to swing over and down upon the closed sections and forcibly draw them together to as tight a fit along the meeting-edges as is necessary.

What I claim is:

1. A bait for drawing glass in plate form 90 consisting of a pair of separable sections pivoted together along their longitudinal edges and having a longitudinal slot between their lower meeting edges and an enlarged interior cavity extending the length of the slot, removable clamping means being employed to hold the sections together in closed relation.

2. A bait for drawing glass in plate form 100 consisting of a pair of sections semi-circular in cross-section hinged together along their top sides and having a slot formed in its under side at the meeting-edges of the sections, removable clamping means being employed to hold the sections together in closed relation.

3. A bait for drawing glass in plate form

consisting of a hollow bait-bar constructed of a plurality of sections and having an entrance slot along its lower edge, and means for exhausting the air from the interior of the bait-bar, removable clamping means being employed to hold the sections together in closed relation.

4. A bait for drawing glass in plate form consisting of a pair of separable sections pivoted together along their upper longitudinal edges and having a longitudinal slot

between their lower meeting edges and an enlarged interior cavity extending the length of the slot, and a clamp pivoted to one of the sections and adapted to swing over and embrace both sections and serve to clamp them solidly together while in closed relation. 15

In testimony whereof I hereunto affix my signature.

GEORGE G. ROBERTS.
